UNITED STATES PATENT OFFICE

EDWARD J. GROSS, OF NEW ROCHELLE, NEW YORK, ASSIGNOR TO BENJAMIN & EDWARD J. GROSS CO., INC., OF NEW YORK, N. Y.

DESIGN FOR A FINGER RING OR ARTICLE OF SIMILAR NATURE

Application filed December 5, 1929. Serial No. 33,664. Term of patent 3½ years.

To all whom it may concern:

Be it known that I, EDWARD J. GROSS, a citizen of the United States, residing at New Rochelle, in the county of Westchester and State of New York, have invented a new, original, and ornamental Design for a Finger Ring or Article of Similar Nature, of which the following is a specification, reference being had to the accompanying drawings, forming a part thereof.

Fig. 2 is a top plan view of the ring in flat arrangement. The portions shown in dotted lines are mere repeats in reverse position of those shown in full outline.

I claim:

The ornamental design for a finger ring or article of similar nature, as shown and described.

In testimony whereof I affix my signature.

EDWARD J. GROSS.
